Primary Examiner — Jennifer L Watkins*Assistant Examiner* — Bryan C Gusman(74) *Attorney, Agent, or Firm* — UltimatEdge IP Law Group, P.C.; Dean G. Stathakis(57) **CLAIM**

The ornamental design for a collapsible camping table, substantially as shown and described.

DESCRIPTION

FIG. 1 is a front, top, left-side perspective view of my design for a collapsible camping table according to the present specification;

FIG. 2 is a rear, bottom, right-side perspective view of FIG. 1;

FIG. 3 is a left-side elevational view of FIG. 1;

FIG. 4 is a right-side elevational view of FIG. 1;

FIG. 5 is a rear plan view of FIG. 1;

FIG. 6 is a front plan view of FIG. 1;

FIG. 7 is a top elevational view of FIG. 1; and,

FIG. 8 is a bottom elevational view of FIG. 1.

The evenly dashed broken lines in the drawings depict portions of a collapsible camping table and form no part of the claim.

1 Claim, 7 Drawing Sheets(56)
